UNITED STATES PATENT OFFICE.

JAMES CRAWFORD, OF DETROIT, MICHIGAN, ASSIGNOR, BY MESNE ASSIGNMENTS, TO CHALMERS MOTOR CORPORATION, OF NEW YORK, N. Y., A CORPORATION OF NEW YORK.

DOOR-CURTAIN-OPERATING-ROD ARRANGEMENT.

1,287,897.

Specification of Letters Patent.

Patented Dec. 17, 1918.

Application filed March 29, 1917. Serial No. 158,296.

To all whom it may concern:

Be it known that I, JAMES CRAWFORD, a citizen of the United States of America, residing at Detroit, in the county of Wayne 5 and State of Michigan, have invented certain new and useful Improvements in Door-Curtain-Operating-Rod Arrangements, of which the following is a specification, reference being had therein to the accompanying 10 drawings.

This invention relates to door curtain operating-rods and refers more particularly to a new and improved arrangement of operating-rod for the body top door curtain 15 of automobiles or the like.

In automobile construction it is desirable to provide some means whereby when the storm curtains are in use the top door curtain can be so supported and operated that 20 it will open and close with the permanent door. It is among the objects of the present invention to provide an improved operating-rod arrangement of this general character and more particularly to provide an improved and simplified construction which 25 can be economically manufactured and applied and will present a neat appearance.

Other objects of the invention are to so construct and arrange the curtain operating-rod that it can be formed from a single piece 30 of iron preferably return-bent upon itself; to provide a construction which can be removably attached to the permanent door, without the use of unsightly brackets or 35 other similar fastening devices; to utilize the spring of the metal or other friction or automatic lock for retaining the door operating rod in position; and in general to provide an improved and simplified construction 40 of rod which can be readily attached to or removed from the permanent door for operating the body top door curtain in union with the permanent door.

In the drawings:

Figure 1 is a side elevational view of an automobile showing the door curtain operating-rod arrangement in use;

Fig. 2 is an enlarged vertical section through the door showing the manner of mounting the rod in the permanent door;

Fig. 3 is a similar view taken at right angles to Fig. 2;

Fig. 4 is a top plan view of the permanent door showing the seat for the curtain operating-rod;

Fig. 5 is a detail view showing the manner of attaching the rod to the curtain;

Fig. 6 is a cross section on the line $x-x$ of Fig. 5.

Describing first in detail the general embodiment of my invention shown in the drawings, A designates the body of the automobile, which body is of the open type, and as shown, is provided with front and rear doors B and C. It is customary with 60 automobiles of this type to provide the top D with side curtains E, and the present invention is directed to an improved arrangement for causing one or more of the curtains E to operate with the permanent door so 65 that in entering or leaving the automobile or other vehicle, the top curtain is swung back when the lower door is opened.

The particular curtain operating-rod arrangement shown in the drawings comprises 75 a rod member F which is return-bent back on itself at G to provide a loop H, while the free ends of the rods J and J' are spaced from each other and connected by inclined portions K and K'. The rod is also offset 80 outwardly at L and preferably inclined from the vertical sufficiently to compensate for the greater width at the top than at the door portion of the vehicle.

For securing the rod in place upon the 85 main door of the vehicle, I preferably employ the following arrangement: Holes M and M are drilled down through the top of the door and fitted with brass or other suitable tubing N and N'. An escutcheon plate 90 O secured to the door by a screw or other securing device O' is positioned with its apertures O² and O³ registering with the upper ends of the tubes N and N'. When it is desired to secure the storm curtain E so that it 95 will be operated in conjunction with the main door, the curtain operating-rod F can be easily secured in place by simply pushing the free ends J and J' down into the tubes N and N'. As there is a tendency of the 100 metal at the lower end of the rod to spring apart there will be sufficient frictional engagement between the inner surfaces of the tubes and the rods J and J' to hold the latter rigidly in place. The use of brackets or 105 other extraneous members is therefore avoided, thus not only producing a neat appearing arrangement but one which can be more readily attached and detached. Also the cost of manufacturing and assembling the 110

parts is reduced to a minimum, and the curtain easily attached to the rod. In the particular construction shown in the drawings, the curtain is provided with a long pocket 5 Q into which the operating-rod F extends.

To obtain good springing on the forked ends of the rods, they are electrically welded or otherwise joined together at about the point marked R so as to prevent spreading 10 of the two rods at the forked ends. While I have described in detail but one of the curtain operating-rod arrangements, it is, of course, apparent that the same or similar construction could be employed on the front 15 door as well as on the rear door, and that various changes in the details of construction, arrangements and combinations of parts can be made within the scope of my invention.

20 What I claim as my invention is:

1. The combination with a door and a curtain, of means for causing the curtain to swing with the door, comprising a rod return-bent upon itself so that its ends are 25 sprung apart, and seats for said ends of the

rod formed in the door, the ends of the rods being frictionally held in place by the springing of the metal.

2. The combination with a door and a curtain, of means for causing the curtain to swing with the door, comprising a rod return-bent upon itself and having spaced forked ends, the two portions of the rod being welded or otherwise joined together to prevent spreading at the forked ends, and 30 seats for receiving said ends arranged to utilize the springing of the metal for frictionally locking the ends of the rod in the seats. 35

3. The combination with a door and a curtain, of means for causing the curtain to swing with the door, comprising a rod having one end formed with spaced apart portions and seats for said spaced apart portions of the rod formed in the door, the spaced apart portions of the rod being 40 sprung when inserted in the seats so as to frictionally lock the rod to the door. 45

In testimony whereof I affix my signature.

JAMES CRAWFORD.
